N. G. NICOLL,
CONVERTIBLE LAMP AND HEATER DEVICE,
APPLICATION FILED JUNE 20, 1916.

1,208,357.

Patented Dec. 12, 1916.

Inventor,
Norman G. Nicoll,
By his Attorney,
A.R. Appleyard

UNITED STATES PATENT OFFICE.

NORMAN G. NICOLL, OF BROOKLYN, NEW YORK.

CONVERTIBLE LAMP AND HEATER DEVICE.

1,208,357.

Specification of Letters Patent. Patented Dec. 12, 1916.

Application filed June 20, 1916. Serial No. 104,688.

To all whom it may concern:

Be it known that I, NORMAN G. NICOLL, a citizen of the United States, residing at Brooklyn, Kings county, New York, have 5 invented a new and useful Improvement in Convertible Lamp and Heater Devices, of which the following is a specification.

My invention relates to a convertible lamp and heater device, the object being to 10 provide a device of the above described class constituted by a stand or pedestal having an electrically connected socket adapted to interchangeably receive the plug of either an incandescent lamp or a heater element 15 for cooking or other purposes, said heater element, when the lamp is in use being stored in the base of the stand or pedestal which is shaped to securely hold the heater against movement therein. 20 I have illustrated a preferred embodiment of my invention in the accompanying drawings, in which, similar reference characters are employed to designate corresponding parts throughout the several views, and in 25 which:—

Figure 1 is a side elevation of my improved convertible lamp and heater device, the base being in section to clearly show the heater and method of storing the same and 30 securing it against movement. Fig. 2 is an elevation showing the heater element in operative position in the socket for cooking and other purposes. Fig. 3 is a plan view of the heater showing one form of coil. Fig. 35 4 shows a modification of the base construction.

In carrying out my invention I provide a stand or pedestal A, comprising a housing or base 10, preferably of sheet metal and having 40 a removable bottom plate 11, held in place by suitable catches, such as teats or beads 12, struck out of a depending flange 13, of the housing, said teats being adapted to enter a circumferential groove 14, formed 45 in an annular flange 15, carried by the bottom plate 11, as clearly shown in Fig. 1 of the drawings. The housing or base 10, is formed at the top of the flange 13, with an inwardly and upwardly curved shoulder portion 16, between which and the bottom plate 11, the heater element 17, is securely held against movement as shown. The housing 50 is provided centrally at the top with a post 18, forked as shown at 19, to receive a

cross pin 20, on which is pivotally mounted 55 an extension 21, of an electrically connected socket 22, having the usual plunger switch button 23, controlling the circuit through the socket to the lamp 24. A shade 25, is adjustably carried on pins 25^a, 60 entering the tops of arms 26, formed on a split sleeve 27, having spring tensional engagement with the socket to support the shade thereon, which construction permits of the quick removal thereof when desired. 65

The heater element 17, in the form of construction shown, comprises a coil chamber 28, receiving the usual heating coil 29, having its terminals confined in the usual plug 30, and an upwardly directed marginal flange 31, is provided around the coil chamber to support cooking vessels or the like as will be readily understood.

The bottom plate 11, is preferably provided with feet or rests 32, as shown. 75

I do not desire to be understood as limiting myself to the detail features and construction and arrangements of parts as herein shown and described, as it is manifest that variations and modifications therein 80 may be resorted to, in the adaptation of my invention to varying conditions of use, without departing from the spirit of my invention and improvements. I, therefore, reserve the right to all such variations and 85 modifications as properly fall within the scope of my invention, and the terms of the following claims.

In the modified construction shown in Fig. 4 of the drawings, I eliminate the bottom 90 plate 11, and shoulder the heater 17, as shown at 17', on which the edge of the depending flange 13, rests, and this construction provides a partial housing for the heater when not in use as clearly shown. 95

What I claim is:—

1. In a device of the class described, a stand having an electrically connected socket adapted to carry a lamp and a hollow base having a circumferential depending flange provided with teats, a bottom plate having an annular flange formed with a continuous groove to receive the teats, said base curved from the top of the circumferential depending flange, inwardly 100 and upwardly to form a shoulder portion, a heater having a marginal flange adapted, 105 when the said heater is stored in the base,

to be confined between the shoulder and the bottom plate to prevent movement thereof, said heater being also provided with a plug adapted in use to enter the socket as and for the purpose set forth.

2. In a device of the class described, a stand having an electrically-connected socket adapted to carry a lamp, said stand being provided with a base forming a housing, and a heater element adapted to be stored in the base when not in use and having means for operative connection with the socket as described.

3. In a device of the class described, 15 a stand having an electrically-connected socket adapted to carry a lamp, and a base forming a housing having a removable bottom, in combination with a heater element having a plug adapted for engagement with 20 the socket for the purpose specified.

4. In a device of the class described, a stand having an adjustable electrically-connected socket adapted to carry a lamp, and a hollow base in combination with a 25 heater element having a plug to engage the socket, said heater being provided with a

coil chamber and a marginal flange for the purpose specified.

5. In a device of the class specified, a stand having a hollow base and a pivoted 30 electrically-connected socket adapted to carry a lamp, a heater element shaped to enter the base when not in use, a removable bottom to said base having an annular flange, said base being also provided with 35 a shoulder adapted, when the heater is stored in the base, to bear on the same to prevent movement thereof said heater having a plug for use in connection with the socket as described. 40

6. In a device of the class described, a stand having an electrically-connected socket adapted to carry a lamp, said stand being provided with a hollow base, and a heater element adapted for use in connection 45 with the socket and being also adapted, when not in use, to be partially housed within said base as shown and described.

In testimony whereof, I have signed my name to this specification this 15th day of 50 June 1916.

NORMAN G. NICOLL.
